UNITED STATES PATENT OFFICE.

MATTHEW W. ENOS, OF CARLINVILLE, ILLINOIS.

SOIL-PULVERIZING MACHINE.

SPECIFICATION forming part of Letters Patent No. 392,320, dated November 6, 1888.

Application filed May 23, 1888. Serial No. 274,837. (No model.)

To all whom it may concern:

Be it known that I, MATTHEW W. ENOS, a citizen of the United States, residing at Carlinville, in the county of Macoupin and State of Illinois, have invented new and useful Improvements in Soil-Pulverizing Machines, of which the following is a specification.

The invention relates to improvements in soil-pulverizing machines; and it consists in the combination of parts hereinafter described, illustrated in the drawings, and pointed out in the appended claim.

Figure 1 of the drawings is a perspective view of a pulverizer-machine embodying the invention. Fig. 2 is a central vertical longitudinal section thereof.

Referring to the drawings by letter, A designates the platform of the machine, having the axle B secured transversely to its under surface across its rear edge and the conveyer-wheels C C on the ends thereof.

c c are chain-wheels formed on the inner sides of the wheels C, concentric with the axles thereof.

D is the driver's seat, resting on the spring-standard d, rising from the platform, and E is a transverse shaft journaled on the front portion of the platform and carrying the fixed chain-wheels e on their ends.

F F are chain-wheels loosely mounted on the ends of the shaft E. The hubs of the said chain-wheels F have their outer edges provided with the inwardly-standing square shoulders f, which engage similar meeting-shoulders, g, on the non-rotatable sleeves G, that ride in and out on the ends of the shaft E, and have at their outer ends the coiled springs G', that bear against said sleeves and against the disks g' on the ends of the shaft E, causing the shoulders f and g to engage.

H H are chains that connect the chain-wheels c and F, moving the latter from the former.

I is a shield-plate extending from the rear edge of the platform and curving downward therefrom, so that it covers the pulverizer-frame J, which has its shaft K journaled at the ends in the rearward extensions j of the side rails of the platform.

k k are chain-wheels on said shaft outside of its bearings, and L L are chains connecting

said wheels with the corresponding chain-wheels, e.

The frame J is composed of the end wheels, m, and the transverse bars M, connecting said wheels and running downward from one side to the other, the said bars being parallel.

N N are teeth standing outward from said bars.

O is the tongue having the clevis o secured to its outer end and journaled upon the platform between the longitudinal bars p p thereof.

P is a curved rack-bar standing upward from the platform and provided with the notches p' on its outer edge, and Q is a lever 65 secured to the rear end of the tongue; passing thence up from its lower end, and having its vertical rod q, which rises adjacent to the driver's seat and is adapted to engage the notches p', so that the tongue can be set higher 70 or lower thereby.

It will be observed that as the machine is drawn over the ground the frame J will be rotated, so as to cause the teeth N to take into and turn up the soil, thereby thoroughly pulverizing the same, so that seed may be properly sowed. When the machine is being drawn forward, the shoulders f of the wheels F engage the shoulders g of the collars G, and consequently rotate the shaft E, and through the 80 said shaft the wheels e and chains I drive the pulverizer-frame. When the machine is pushed backward, however, the shoulders f will slip past the shoulders g, so that the pulverizer-frame will not be rotated and the teeth 85 bent or otherwise injured. The coiled springs serve to keep the collars normally pressed toward the wheels F, but allow the said collars to yield readily to allow the shoulders f to slip past the shoulders g when the machine is 90 going backward.

By means of the lever Q and its connections the machine can be quickly adjusted to cut to a greater or less depth while the machine is in motion.

Having described my invention, I claim—

The combination of the frame, the axle mounted thereon, the carrying-wheels mounted on the axle, the shaft E, journaled transversely in the front end of the frame, the wheels e, secured to said shaft, the wheels c on the axle, 100 geared to the wheels e, the wheels F, loosely

mounted on the shaft E and having the shoulders *f*, the sliding collars G, mounted on the shaft E and having the shoulders *g* engaged by the shoulders *f*, springs coiled around the 5 shaft E and normally pressing the collars G toward the wheels F, and the pulverizing-frame at the rear end of the frame provided with the wheels K, geared to the wheels F, as specified.

In testimony that I claim the foregoing as my own I have hereto affixed my *si* nature in presence of two witnesses.

MATTHEW W. ENOS.
